UNITED STATES PATENT OFFICE

2,691,510

LIQUID DELIVERY DEVICE IN WHICH
LIQUID IS DRAWN INTO AN AIR CUR-
RENT BY SUCTIONCharles J. Manville, Pontiac, Mich., assignor to
Manville Manufacturing Corporation, Pontiac,
Mich., a corporation

Application June 1, 1953, Serial No. 358,923

1 Claim. (Cl. 261—78)

1

This invention relates to a liquid delivery device comprising in general an open top one piece liquid container in which there is removably and slidably received a liquid delivery tube. The device of this invention is particularly adaptable for use in connection with a dish washing apparatus of the character shown and disclosed in my Patent No. 2,652,850, issued September 22, 1953, entitled "Back Flow Preventing Unit For Dishwashing Apparatus."

Liquid delivery devices of the general character of this invention have been heretofore employed in various capacities wherein it is desired to withdraw liquid from the container by suction in a materially reduced quantity as in a lubricant device for internal combustion engines, and particularly for introducing a minute quantity of liquid detergent into the water stream of a dish washing apparatus of the character disclosed in the co-pending application to which reference herein is specifically directed.

In such devices there is generally a sealing cap for the container in which the suction tube is a fixed and permanent part, as in a lubricating device, or wherein the container is open at the top, but with the tube extending through one wall thereof, as in the above-mentioned application. In all such devices, in operation one end of the tube is open to the atmosphere above the level of the liquid while the other end of the tube is connected by a suction conduit to a source of partial vacuum. The lower portion of the tube adjacent the body of the container and wall within the liquid is provided with a small intake aperture so that the major portion of the suction is accommodated by the air entering the upper end of the tube and the minor portion by a stream of liquid induced by the air flow through the small aperture at the bottom of the tube.

It is the purpose of this invention to simplify such devices while rendering them equally effective, and particularly wherein it is desirable to employ a one piece molded plastic container having no tube supporting top or cap and no openings in the walls. This is accomplished by forming an open top one piece plastic container with a pair of opposed and aligned vertical grooves in opposite walls for slidably receiving and retaining in proper position a yielding U-shaped tube under its inherent spring tension. One leg of the U-shaped tube seating in one groove terminates in an open end adjacent the upper edge of the container, the other leg seating in the opposite groove and extending over the upper edge of the container for connection with a suction conduit.

2 The intermediate curved portion of the U-shaped tube lies adjacent the bottom of the container with its top surface provided with a minute liquid intake aperture.

5 By reason of this structure the entire device consists of only two parts with no closure fittings or holes in the walls, namely, a one piece open top container into which a liquid delivery tube may be readily inserted or withdrawn for container

10 cleansing.

The full nature of the invention will be understood from the accompanying drawings and the following description and claim:

Fig. 1 is a perspective view of the container with the tube removed, and comprising one unit of the device.

15 Fig. 2 is a side elevation of the U-shaped delivery tube in its uncompressed or expanded position shown in full lines and adapted to be compressed under its inherent spring tension to the position shown in dotted lines.

20 Fig. 3 is a transverse section through the container and tube slidably mounted therein.

25 Fig. 4 is a plan view of the container with the tube mounted therein.

In the drawings there is shown a one piece cast or moulded liquid container having a bottom 10, end walls 11 and side walls 12. Said container may be of any material, but preferably moulded or cast of plastic. One side wall 12 is formed with a pair of bracket members 13 formed therein for providing a support by which the container may be mounted in operative position. Internally of the container a pair of opposed walls are formed with aligned vertical grooves 14. There may be additional grooves at different locations in the container for selective positioning of the tube as indicated at 14'. Said container may be filled with the liquid to be delivered, such as a liquid detergent to be drawn by suction therefrom as more particularly set forth and described in the above-mentioned application for Letters Patent.

40 The second unit of the device consists of a U-shaped yieldable tube having opposed leg members 15 and 16 joined by an intermediate curved bottom portion 17. Said tube is preferably made of slightly springy material, such as copper so that the leg members may be forced into parallel relation as indicated by dotted lines in Fig. 2, to exert an outward pressure under their inherent spring tension. The leg member 15 is open to the atmosphere while the leg member 16 terminates in a reverse bend indicated at 18 to provide

55 an overhanging delivery end for connection with

3

a flexible suction tube 19. The curved bottom portion 17 is provided with a minute intake aperture 20.

In assembly, the U-shaped tube is slidably inserted downwardly into the container with the legs 15 and 16 being positioned and guided within the grooves 14. Due to the inherent spring tension when forced into the container, the leg members assume the position shown in dotted lines in Fig. 2, and thereby exert sufficient friction within the grooves of the container to maintain the tube in its properly seated position. The overhanging delivery end 18 of the tube may be slidably connected with the flexible suction tube 19. The container may then be filled to the level indicated at 21 with a liquid detergent which is drawn through the aperture 20 of the delivery tube along with a quantity of air drawn through the open exposed end of the leg member 15.

The suction for drawing the air and liquid into the tube is created by a partial vacuum developed in the suction tube 19 by means of a manually and selectively controlled venturi positioned in a stream of water under pressure, all as more particularly set forth and described in said application. Since it is desirable to periodically clean the container and tube to remove sediment or coagulated detergent, it is very simple due to the structure of this device, to slide the U-shaped tube from the container so that they can be conveniently cleaned independently of each other and readily reassembled.

The invention claimed is:

4

A liquid delivery device comprising a one piece liquid container open at the top and having bottom and side walls, said container being provided with a pair of vertical grooves in the inner surface of opposite walls and in opposed alignment, a yielding U-shaped tube having opposed leg members seatable in said grooves respectively under inherent spring tension and slidably into supporting engagement therewith, the intermediate bottom portion of said tube lying adjacent the bottom of the container, one end of said tube being open to the atmosphere substantially at the upper edge of one wall of the container and the other end extending over the upper edge of the opposed wall and curved downwardly therefrom to provide an overhanging delivery and for connection with a suction conduit, and a restricted liquid inlet opening in the intermediate bottom portion of the U-shaped tube to lie adjacent the bottom of the container and be submerged in liquid contained therein.
